ABSTRACT: A trot line holder for carrying a trot line and the stages to be secured thereto having a base member and a reel and a pair of coaxially mounted rotatable tables thereon, adapted to receive the stages and maintain them ready to be mounted on the line after the line is set, said tables having means for receiving and maintaining the hooks of the respective stages in hook-receiving slots and the connecting pins of the respective stages in pin-receiving ports, preventing a tangle of stages while the line is being transported.

PATENTED AUG 24 1971

3,600,839

TROT LINE HOLDER

SUMMARY OF THE INVENTION

A trot line holder having a rotatable axle and tables mounted on said axle, a reel on said axle upon which a trot line is mounted, and a plurality of stages having hooks on one end and pins on the other end, mounted on said tables, means for maintaining the hooks in position on the tables and a fixed base member and a cover and means for releasably mounting said cover on said base member.

BRIEF DESCRIPTION OF THE DRAWINGS

FIG. 1 is an elevational perspective view of the assembled device.

FIG. 2 is a side elevational view in cross section, and

FIG. 3 is an end view of the device, taken on the line 3—3 of FIG. 2.

DESCRIPTION OF THE PREFERRED EMBODIMENT

In the drawings the numeral 1 designates a base member to which the securing arm 2 is attached, and on the extended end of said securing arm 2 is the clamp 3 which may be used to anchor the device to the seat or the deck of a boat. Axially positioned in said base member 1 is the bearing 4 in which the shaft 5 is mounted, said shaft 5 having the external threads 6 to receive the seat 7 and on which the lower table 8 is anchored by means of the internally threaded flange 20. Mounted on the lower table 8 are the supporting posts 9, 9 which are secured at one end to the lower table 8 and at the other end to the intermediate table 10 by means of the internally threaded flanges 11, 11 and the tables 8, 10 are maintained spaced apart by the tubular members 12, 12, which telescope into said posts 9, 9. An upper table 13 is mounted on the table 10 as by means of the supporting shafts 14, which are threaded at one end as at 22, and are received into the threaded ports as 24 in the upper table 13 and are diametrically reduced at the other end as at 23, which ends are seated in ports formed in the intermediate table 10 adjacent the posts 9. The intermediate table 10 has a downwardly extending peripheral flange 15 provided with a plurality of spaced horizontal ports 16, and the upper table 13 has the downwardly extending flange 17, and the upwardly extending teeth 18, 18. Each of the tables 8, 10, 13 are provided with an axial port through which the tubular shaft 19 extends.

A cover 25 fits over the device, and a pair of J-slots 26 receive the projecting studs 27 mounted in the base member 1, and a felt ring 28 is mounted in the top of the cover 25 in position to bear against the teeth 18 to prevent the hooks 29 from leaving the space between the teeth during transit of the device by the user and acting as an anchor preventing the rotation of the tables while the cover is in place. A handle 30 provides means for carrying the assembled device, and a knob 31 provides a gripping means for lifting the cover off of the base member.

Rotatably mounted on the shaft 19 is the reel 32 on which a line may be wound for use in setting a trot line.

In use the cover 25 is removed and the stages consisting of

the short lines 33 having the hooks 29 mounted on one end and the pins 34 mounted on the other end will be stored by suspending the hook 29 from the upper table 17, placing the curved portion of each hook between two of the teeth 18, with the pointed barb 35 extending downwardly through the ports 36, and the pins as 34 extending through the ports 16 in the intermediate table 10. In making up a trot line, the device may be anchored to a boat by means of the clamp 3, and the upper and intermediate tables, 13, 10, may be lifted off of the shaft 19, and the reel 32 thus exposed, so that one end of the line wound on the reel 32 may be secured to a post, or whatever is being used to form one anchor for the trot line, and the boat then moved, permitting the line on the reel to be dispensed, until the other anchor point is reached, where the other end of the line on the reel may be freed from the reel and secured to the second anchor means. If desired, a ring may be secured to one end of the line and another ring of less diameter secured to the boat, and the line extended through the smaller ring, so that the end of the line will not be inadvertently lost overboard if the boat travels beyond the length of the line. Also, if desired, the reel 32 may be removed from the shaft 19 and, after the one end of the line has been anchored, a rod inserted through the reel and held in the hands of the user as the line is dispensed. After the line has been anchored at both ends, the tables 10 and 13 are replaced on the shaft 19 and as the boat travels back over the line between the two anchor points, the stages are mounted on the line at spaced intervals by lifting the respective hooks from the upper table and releasing the pin on the other end of the stage from the lower table and securing the pin to the line. In taking up the trot line this procedure is reversed. The upper table 13 has the annular partition 36' providing a storage chamber for such accessories as extra weights, as 37, 37.

What I claim is:

- 35 1. A trot line holder having a stationary base member, spaced tables rotatably mounted on said base member, a reel mounted on one of said tables, and another of said tables having means for receiving hooks of stages to be mounted on a trot line, and another table having means for receiving the pins of said stages.
- 20 2. The device defined in claim 1 wherein said base member supports said tables in spaced relation by means of telescoping shafts between said tables and an axial shaft extending through part of said tables.
- 25 3. The device defined in claim 1 wherein the uppermost of said tables is provided with a series of upwardly projecting spaced teeth on the outer periphery thereof, and a series of vertical ports in alignment with the spaces between said teeth.
- 30 4. The device defined in claim 1 wherein the uppermost of said tables is provided with a series of upwardly projecting spaced teeth on the outer periphery thereof, and a series of vertical ports in horizontal alignment with the spaces between said teeth, and the intermediate table is provided with a downwardly extended peripheral flange having spaced horizontal ports extending therethrough in vertical alignment with the spaces between said teeth.
- 35 5. The device defined in claim 1 wherein a cover for said device is provided having yieldable means mounted therein to bear against the uppermost table, and means for anchoring said cover in position on said base member.
